UNITED STATES PATENT OFFICE

2,565,846

MEANS FOR PRODUCING KNITTED METALLIC MESH STRUCTURES

Alfred M. Goodloe, Upper Montclair, N. J., assignor to Metal Textile Corporation, West Orange, N. J., a corporation of Delaware

Application August 29, 1947, Serial No. 771,324

6 Claims. (Cl. 140—107)

1

This invention relates to means for producing a novel filter body medium; and the invention has reference, more particularly, to a novel filter body medium produced from tubular knit metallic mesh, and adapted for forming the foraminous mass of various kinds of impingement type air and gas filters, oil bath type filters, as well as for other uses wherein an interstitial body mass is required.

In the use of tubular knit metallic mesh for forming a foraminous filter body, it has heretofore been known to flatten a suitable length of tubular knit mesh into a double ply strip of suitable width, and then roll said strip upon itself to form the mass of the filter body. Preparatory to thus rolling the flattened tubular mesh strip, it has also been known to first corrugate or crimp the strip transversely at an angle other than ninety degrees to the length of the strip, and then superimpose a plurality of corrugate strips so that the corrugations or crimps of contiguous strips cross each other. When a flattened tubular knit metallic strip is thus corrugated or crimped, the corrugating operation tends to nest the corrugations or crimps of one ply thereof into those of the opposed ply, with the wire strands of the respective plies tending to lie closely parallel in an approximate double strand formation or relation, so that the mesh differs little from a single ply mesh strip formed from wire having the thickness of the two strands. Such effect is not satisfactory in that the strands of wire constituting the mesh are neither suitably separated or substantially uniformly distributed throughout the area and mass of the filter body formed from the mesh; and, furthermore, the interstitial spaces formed by the mesh loops tend to remain fully open, so that the filter body formed from the mesh is of unduly coarse porosity, involving risk of escape of solids desired to be separated from fluid streams which traverse the filter body.

Having the above conditions and effects in view, it is the purpose of this invention to provide means for producing corrugated or crimped flattened tubular knit metallic strip in which the corrugations or crimps of contiguous plies thereof are disposed in non-nesting relation; in which the wire strands of knitted mesh are more efficiently separated and relatively more uniformly distributed throughout the area and mass of the strip; and in which the interstices of the tubular knit strip are more uniformly distributed and at the same time, in effect, both reduced in area and substantially doubled in number, where-

by to provide a filter body formed from the mesh of more uniform and finer porosity.

More specifically the invention seeks to provide means for producing corrugated or crimped flattened tubular knit metallic strip, the opposed plies of which are so refolded and related that the corrugations or crimps of the redispersed plies are each given a herringbone disposition, and are so mutually related that superposed corrugations or crimps of the opposed plies will cross one another in non-nesting relation; with the advantage that a single strip of such herringbone formation may be rolled upon itself, or portions thereof otherwise superposed, to form a filter body, without necessity for employing two strips superposed with their respective corrugations or crimps in crossed relation as has been heretofore necessary.

20 The invention has for a further object to provide novel apparatus which is operative to refold a corrugated or crimped flattened tubular knit metallic mesh strip, whereby to automatically produce the above stated herringbone form and non-nesting relation of the corrugations or crimps of its resultant opposed plies.

25 The invention is illustrated in the accompanying drawings, in which:

Fig. 1 is a top plan view, Fig. 2 is a side elevational view; and Fig. 3 is a central longitudinal sectional view of apparatus operative to refold a corrugated or crimped flattened tubular knit metallic mesh strip so as to convert the same into herringbone form.

30 Fig. 4 is a schematic plan view of a strip of flattened tubular knit metallic mesh, as provided with angularly transverse corrugations or crimps, and thus in initial condition ready to be converted into the novel herringbone form according to this invention.

35 Figs. 5 to 8 inclusive are respectively cross-sectional views illustrative of successive steps of the operation of refolding a corrugated or crimped flattened tubular knit metallic mesh strip, whereby to convert the same into the novel herringbone form according to this invention.

40 Fig. 9 is a schematic plan view of the corrugated or crimped tubular knit strip after conversion of the same into the novel herringbone form according to this invention, a portion of the upper ply thereof being broken away to disclose the underlying ply having its corrugations or crimps disposed to cross those of said upper 45 ply in non-nesting relation.

45 Similar characters of reference are employed

in the above described views, to indicate corresponding parts.

The novel filter body medium according to this invention is produced from a length of tubular knit metallic mesh of suitable diameter which is initially flattened so as to provide a two-ply strip comprising the obverse ply 10 and contiguous reverse ply 11.

The thus flattened two-ply strip is next passed through the nip of a pair of corrugating or crimping rolls of such character as will corrugate or crimp the strip transversely at an angle relative to the length of the strip which is other than ninety degrees, whereby to form a continuous succession of diagonal corrugations or crimps across the width of the strip. As so corrugated or crimped, the corrugations or crimps 13 of the reverse ply 11 tend to nest into the corrugations or crimps 12 of the obverse ply 10 (see left end of Fig. 4). The tubular knit metallic strip, as thus initially formed, provides the base material which is subject to conversion into the novel herringbone form of strip according to this invention.

The tubular knit metallic mesh strip as thus initially formed having been provided, the same is subjected to refolding operations by means of an apparatus or machine which will now be described.

Said refolding apparatus or machine comprises a base 20. Rising from the sides of said base 20, at the forward end of the latter, are bearing plates or members 21. Journaled in and across said bearing plates or members 21 are a pair of longitudinally spaced lower shafts 22 and 23, and a pair of similarly longitudinally spaced upper shafts 24 and 25. Preferably, the shafts 22 and 24 are relatively disposed in vertical alignment, and similarly the shafts 23 and 25 are also disposed in vertical alignment.

Respectively fixed on the lower shafts 22 and 23, in central positions intermediate the bearing plates or members 21, are pulley wheels 26 and 27 over which runs and by which is driven an endless belt 28. In like manner, respectively fixed on the upper shafts 24 and 25, in opposition to the pulley wheels 26 and 27, are other pulley wheels 29 and 30 over which runs and by which is driven a second endless belt 31, the lower course of which is opposed to the upper course of said belt 28, whereby to cooperate with the latter for operatively engaging the tubular knit metallic mesh strip to be moved through and operated upon by the machine, whereby to guide the run of the strip and hold said strip against lateral displacement or shift.

Fixed on the lower shaft 23 are a pair of mesh strip propelling wheels 32 which are respectively disposed on opposite sides of the pulley wheel 27 in equi-spaced relation to the latter. Fixed on the upper shaft 25 is a like pair of mesh strip propelling wheels 33 which are opposed to the propelling wheels 32. Said propelling wheels 32 and 33 are provided with a plurality of circumferentially spaced mesh strip engaging spurs 34 which project radially from the peripheries thereof. The spurs 34 of the wheels 32 are disposed in staggered relation to those of the wheels 33, so that the same substantially intermesh, being thus adapted to penetrate a mesh strip engaged between the wheels 32 and 33, so that the latter will operate to transmit a positive forward propelling movement to the mesh strip. Said mesh strip propelling wheels are laterally spaced apart for a distance somewhat less than the width of a flattened tubular knit mesh strip, whereby said

wheels will operatively engage opposite lateral marginal portions of said strip.

One of said shafts, as e. g. the shaft 22 constitutes the drive shaft of the machine, to which operating power may be applied by any suitable power transmission means. Fixed on the shaft 22, at one side of the machine, is a gear wheel 35 which drives a similar gear wheel 36 on the shaft 23 through an interposed idler gear 37, whereby said lower shafts and the pulleys and belt and mesh strip propelling wheels driven thereby are rotated in common counterclockwise direction. Fixed on the shafts 22 and 24, at the opposite side of the machine, are intermeshing gear wheels 38 and 39, and similarly fixed on the shafts 23 and 25, at said opposite side of the machine, are intermeshing gear wheels 40 and 41, whereby the pulleys and belt and mesh strip propelling wheels driven by said shafts 24 and 25 are rotated in common clockwise direction, so as to cooperate with the pulleys and belt and mesh strip propelling wheels driven by the shafts 22 and 23 for moving a mesh strip operated upon through the machine.

Disposed rearwardly of the mesh strip propelling mechanism above described is a mesh strip refolding mandrel. Said mandrel comprises a longitudinally extending main body or plate 42 which is disposed in perpendicular plane, at least the forward portion of which is shaped to possess incline margins 43 which are convergent upon its forward extremity 44. Connected with the forward portion of said main body or plate 42, to extend in a central horizontal plane which intersects the longitudinal axis of said main body or plate 42, and respectively projecting from opposite sides of said main body or plate, are refolder fins. The forward portions 45 of said refolder fins are substantially coincident to the forward extremity of said main body or plate 42, and the combined lateral extent of said forward portions approximates the width of the flattened tubular knit mesh strip to be operated upon. Said refolder fins are provided with sides 46 which converge upon the faces of the main body or plate 42 at points intermediate the forward and rearward ends of the latter.

Said mandrel is floatingly supported with its main body or plate 42 aligned in the plane of the pulleys and belts of the above described mesh strip propelling mechanism. To this end, the lower margin of said main body or plate 42 is supported by a freely rotatable, peripherally grooved carrier wheel 47, the latter being mounted on a bearing bracket 48 which is affixed to the machine base 20. The rearward end of the mandrel is held against lateral displacement between a pair of guard posts 49, which are suitably affixed to the base 20 to upstand therefrom in straddling relation to the main body or plate 42 of the mandrel. The forward end of the mandrel is also held against lateral displacement between a pair of perpendicular guard rollers 50 which are disposed contiguous to the forward ends of the refolder fins of the mandrel in straddling relation thereto. Said guard rollers 50 are rotatably mounted on journal posts 51, which are also suitably affixed to the base 20 to upstand therefrom.

In the use of the above described apparatus or machine whereby to refold an initially corrugated or crimped flattened tubular knit metallic mesh strip into the novel herringbone form of strip according to this invention, said initial strip is telescoped over the floating mandrel, and its forward end passed between the opposed medial

belts 28 and 31 and between the opposed propelling wheels 32 and 33 so as to be operatively engaged by these elements whereby, when power is applied to the machine, said mesh strip will be progressively advanced over the floating mandrel with accompanying desired refolding effects.

As the initial mesh strip moves onto the mandrel, its edge folds *a* and *b* will be engaged by edges of main body or plate 42 of the mandrel (see Fig. 5). As the strip progresses along the mandrel, the respective medial portions *c* and *d* of its initial plies 10 and 11 will ride onto and move forwardly along the inclined and forwardly divergent sides 46 of the refolder fins of said mandrel. The angle of convergence of the edges 43 of the forward portion of the main body or plate 42 is substantially complementary to the angle of divergence of the sides 46 the refolder fins, and, as a consequence of this, the medial portions *c* and *d* of the respective plies 10 and 11 of the tubular mesh strip will be spread apart proportionately to the movement of the edge folds *a* and *b* of the strip one toward the other. As such relative movements of the edge folds and medial portions of the mesh strip progresses, the obverse ply 10 of the strip will be divided into panels *e* and *f* and, in like manner, the reverse ply 11 of the strip will be divided into panels *g* and *h* (see Fig. 6). As the movement of the strip along the mandrel continues, the obverse ply will be doubled back upon itself along its medial line and similarly the reverse ply will be doubled back upon itself along its medial line (see Fig. 7), until finally, as the strip passes off of the mandrel (being drawn therefrom by the strip propelling mechanism of the machine) the panels *e* and *f* will be brought together in face to face opposed relation and the panels *g* and *h* will be similarly brought together in like face to face opposed relation, with the panels *e* and *g* disposed in substantially common plane to form one ply and the panels *f* and *h* disposed in substantially common plane to form the other ply of the refolded mesh strip (see Figs. 8 and 9).

In the refolded corrugated or crimped tubular knit mesh strip, the folding of the initial corrugate plies transversely upon themselves results in disposing the corrugations or crimps of the re-formed plies so that the same extend in divergent relation from medial portions of the respective re-formed plies in a herringbone pattern, and so that the herringbone pattern of the obverse re-formed ply comprises corrugations or crimps 12' and 13' divergently directed toward one end of the refolded strip, while the herringbone pattern of the reverse re-formed ply comprises corrugations or crimps 12'' and 13'' divergently directed toward the opposite end of the refolded strip (see Fig. 9). By reason of this, the herringbone pattern of corrugations or crimps of the obverse re-formed ply will cross those of the reverse re-formed ply, and consequently said corrugations or crimps can not nest together, nor can corrugations or crimps of superposed refolded strips or strip portions nest together. Furthermore, the crossing of the corrugations or crimps of the re-formed plies of the refolded strip tends to better assure separation and crossing of strands of the knit loops of one re-formed ply relative to those of the opposite re-formed ply, whereby a more uniform distribution of wire and a multiplication and better distribution of the interstices of the mesh strip and of foraminous bodies formed therefrom is assured; all to the end

that a vastly improved medium for fluid filtration and similar purposes is provided.

Having now described my invention, I claim:

1. A machine for the purposes described comprising a refolding mandrel formed by a mandrel plate disposed in perpendicular plane and provided with a forwardly tapered discharge portion defined by inclined margins converging upon its forward discharge end, rearwardly tapered refolder fins respectively projecting from opposite sides of the tapered discharge portion of the mandrel plate in a horizontal plane intersecting the longitudinal axis of said mandrel plate, the combined width of the forward discharge ends of said refolder fins approximating the internal width of a tubular mesh strip to be refolded, said forward discharge ends of the refolder fins being positioned in substantial alignment with the discharge end of the mandrel plate, means to floatingly support said refolder mandrel, driven means beyond the discharge end of the refolding mandrel operative to draw and advance the tubular strip thereover, and driven opposed endless belts aligned with the longitudinal axis of the refolding mandrel between contiguous runs of which the refolded tubular strip passes from said mandrel whereby to guide the strip and hold the same against lateral shifting displacement.
2. A machine as defined by claim 1 wherein the means for drawing and advancing the strip over the refolding mandrel comprises driven pairs of opposed strip propelling wheels disposed to engage marginal portions of the refolded strip, said wheels having radial spurs to engage through the mesh of the strip material.
3. A machine as defined by claim 1 wherein the means to floatingly support the refolding mandrel comprises a pair of upstanding guard posts to straddle the rearward end of the mandrel, a pair of upstanding guard rollers to straddle the forward end of the mandrel, and a grooved carrier wheel cooperative with the lower margin of the mandrel plate.
4. A machine as defined by claim 1 wherein the means to floatingly support the refolding mandrel comprises a pair of upstanding guard posts to straddle the rearward end of the mandrel, a pair of upstanding guard rollers to straddle the forward end of the mandrel, and a grooved carrier wheel cooperative with the lower margin of the mandrel plate, and wherein the means for drawing and advancing the strip over the refolding mandrel comprises driven pairs of opposed strip propelling wheels disposed to engage marginal portions of the refolded strip, said wheels having radial spurs to engage through the mesh of the strip material.
5. In a machine for the purposes described, a refolding mandrel formed by a mandrel plate disposed in perpendicular plane and provided with a forwardly tapered discharge portion defined by inclined margins converging upon its forward discharge end, rearwardly tapered refolder fins respectively projecting from opposite sides of the tapered discharge portion of the mandrel plate in a horizontal plane intersecting the longitudinal axis of said mandrel plate, the combined width of the forward discharge ends of said refolder fins approximating the internal width of a tubular mesh strip to be refolded, said forward discharge ends of the refolder fins being positioned in substantial alignment with the discharge end of the mandrel

plate, and means to floatingly support said refolding mandrel.

6. In a machine for the purposes described, a refolding mandrel formed by a mandrel plate disposed in perpendicular plane and provided with a forwardly tapered discharge portion defined by inclined margins converging upon its forward discharge end, rearwardly tapered refolder fins respectively projecting from opposite sides of the tapered discharge portion of the 10 mandrel plate in a horizontal plane intersecting the longitudinal axis of said mandrel plate, the combined width of the forward discharge ends of said refolder fins approximating the internal width of a tubular mesh strip to be refolded, said forward discharge ends of the refolder fins being positioned in substantial alignment with the discharge end of the mandrel plate, and means to floatingly support said refolding mandrel, said latter means comprising 20 a pair of upstanding guard posts to straddle the rearward end of the mandrel, a pair of upstanding guard rollers to straddle the forward end

5 of the mandrel, and a grooved carrier wheel cooperative with the lower margin of the mandrel plate.

ALFRED M. GOODLOE.
